ATTORNEY.

UNITED STATES PATENT OFFICE.

OTTO A. MICHELIS, OF DETROIT, MICHIGAN.

WIRES LOOP.

Application filed April 13, 1921. Serial No. 461,143.

To all whom it may concern:

Be it known that I, OTTO A. MICHELIS, a citizen of the United States, residing at Detroit, in the county of Wayne and State 5 of Michigan, have invented certain new and useful Improvements in Wire Loops, of which the following is a specification.

This invention relates to wire loops for connecting springs and wires and to a disposition of the end portions thereof whereby the loop may be readily snapped over a wire, the jaws of the loop being so arranged with respect to the wire that it readily enters between the same.

15 The invention consists in the matters hereinafter set forth, and more particularly pointed out in the appended claims.

In the drawings, Fig. 1 is a view of a pair of springs united by a loop that embodies 20 features of the invention; Fig. 2 is a view of a loop slightly spread by the insertion of a wire, the latter being omitted for a clear view; Fig. 3 is a view of a loop showing the position the jaws or arms thereof assume 25 when forced against the wire; Fig. 4 is a view showing the position assumed as the wire enters further between limbs of the loop; Fig. 5 and 6 are views in detail of the loop without the wire.

30 As herein shown, a loop 1 is formed of a piece of spring wire, bent between its ends to form parallel arms 2 and 3, the end portions of which are disposed so that a return limb 4 of the arm 2 overlies the arm 3 while a corresponding member 5 of the arm 3 underlies a portion of the arm 2; the bend 7 which unites the parts 3 and 5 extending sufficiently beyond the bend 6 which unites the parts 2 and 4 so that an entrance angle is formed 35 by the overlap. In use, a wire 8 when pressed into this angle formed by the overlapping bends 6 and 7, forces the arms apart and is readily slipped along as indicated in Figs. 3 and 4, until it clears the shorter 40 limbs. This complete entrance into the loop permits the latter to be turned as indicated in Fig. 1 for loosely articulating two inserted wires 9 and 10.

45 A feature of the invention is the overlapping of the loop ends to form an entrance angle into which an applied wire may be read-

ily placed, thus permitting the loop to be forced home over the wire without the necessity of first spreading or opening the loop, either by pliers or by the fingers of 55 the operator. This greatly increases the efficiency of the loop and ease of its operation, a matter which is of great moment where large numbers are used, as in spring seat constructions, and when once applied, 60 the loop is self-locking against any accidental disengagement.

Another feature is the resistance afforded to opening of the loop when the two wires which the loop secures tend to move apart. 65 If the inner bend commences to straighten out, the strain comes on the second loop and the latter of course has to straighten out in reverse direction to the first loop. Consequently there is a double resistance to end- 70 wise pull on the loop and the added strength caused by the opposing, straightening motions of the free arms.

Obviously changes in the detail of construction may be made without departing 75 from the spirit of the invention, and I do not care to limit myself to any particular form or arrangement of parts.

What I claim is:

1. The combination in a spring structure 80 comprising a plurality of coiled springs and ties therefor each consisting of a wire loop the arms of which terminate in oppositely disposed hooks disposed in superimposed relation with the bight of one hook projecting slightly beyond the other, facilitating the engagement of the loops with adjacent springs, one coil normally lying in the closed end of the loop and the other within both of 85 said hooks.

2. In a spring structure, the combination of a plurality of coiled springs and tie loops therefor having arms terminating in hooks disposed in oppositely facing superimposed relation with the bight of one hook projecting beyond the bight of the other, facilitating the engagement of the loops with the coils of the springs, the bills of the hooks being relatively short, further facilitating 95 such engagement.

In testimony whereof I affix my signature.

OTTO A. MICHELIS.
